UNITED STATES PATENT OFFICE.

ASHLEY C. BENNETT, OF MINNEAPOLIS, MINNESOTA.

GRAVITY AIR CLEANER FOR CARBURETORS.

Application filed May 18, 1925. Serial No. 31,064.

My invention relates to gravity air cleaners for carburetors, more particularly adapted to use upon carburetors of automobiles, trucks and the like.

5 It is the object of my invention to provide a simple, compact and efficient device adapted to remove from the air going into the carburetor of a gas engine the particles of dust and dirt borne in or upon said air. To that 10 end I provide the novel features of construction herein described and claimed.

The full objects and advantages of my invention are more fully described in the specification, and its novel features are particularly pointed out in the claims.

In the drawings illustrating one form of my invention,—

Fig. 1 is an elevation side view of my air cleaner as it will appear when connected with the intake of an internal combustion or gas engine. Fig. 2 is an edge view of the member shown in Fig. 1. Fig. 3 is a sectional elevation on line 3—3 of Fig. 2 viewed in the direction of the arrows. Fig. 4 is a sectional elevation across the carburetor taken on the line 4—4 of Fig. 3 and viewed in the direction of the arrows. Fig. 5 is a sectional plan view taken on the line 5—5 of Fig. 3 viewed in the direction of the arrows.

30 My carburetor attachment comprises a cylindrical casing 10 provided with an upper opening 11 communicating with the upper portion of an inlet pipe 12. The casing 10 is projected across a part of the opening 11 in a somewhat inwardly-turned lip 13. At the bottom the casing 10 is separated and the members lapped past one another forming a tangential opening as indicated at 14 in Fig. 3, this opening being across the cylindrical member 10 and formed between its outer wall and the inwardly-projected lip 15 extended from a portion of the cylindrical member 10.

To the cylindrical member 10 is secured at the center of its transvertical diameter an 45 internally-threaded boss 16 which surrounds the opening 14; and into this boss is threaded the neck 17 of a receptacle 18 which may conveniently be a glass jar of the type used for canning.

50 The back of the cylinder 10 is closed by a disc-like member 19 which may have a circumferential flange 20 embracing the cylinder 10 and may be soldered, welded or otherwise secured thereto. The back member 19 is provided with a central cylindrical open-

ing 21 which is surrounded by an outwardly-projected circumferential flange 23. To the flange member 23 is secured by soldering or otherwise an elbow 24 of an outlet pipe 25 which is directly connected with the intake to 60 the carburetor.

The front of the cleaner comprises an annular disc 26 having a flange 27 which embraces the cylindrical casing member 10 and is secured thereto by soldering, welding or in 65 any desired way. The annular disc 26 is provided with a flange 28 surrounding its inner end and extending outwardly which is adapted to be engaged by a removable disc 29 having a flange 30 engaging over the 70 flange 28 of the annular disc 26, said closure 29 being removably held in position by means of a thumb nut 31 threaded upon the stem of a bolt 32 which bolt has its inner end secured by a screw 33 upon a spanner 34 extending across the opening 21 in the back member 19 and has its threaded end extending through a central opening in the front member 29.

These parts are so constructed that when 80 the thumb nut 31 is screwed upon the front member 29 an airtight connection is effected so that the air admission opening 11, the air outlet opening 21 and the dust receptacle opening 14 are the only openings into the 85 chamber formed by the cylindrical casing member 10 and the front and back members.

In this form of construction, when the motor is operating the suction induced by the motor and by which the air is drawn through the carburetor and the intake manifold into the cylinder of the engine causes the air to move rapidly through the intake pipe 12 and the contracted tangential opening 11 therefrom, with the result that said air and the 90 dust that it carries is caused to whirl rapidly about the cylindrical casing member. This movement causes the particles of dust to be thrown by centrifugal force to the outside of the casing member, which also is aided by 95 gravity in the lower portion thereof so that said particles of dust will move through the tangential opening 14 into the dead air space within the receptacle 18, where they will gravitate to the bottom and be permanently 100 separated from the communicating air.

It may be desirable to provide in addition to the direct air-separating means above described a separate filter or strainer for removing the exceedingly minute and small 110

quantity of dust particles not removed by the direct action of the cleaner, and such strainer member must be easy of insertion and removal into the cleaner to permit of frequent washing. To that end I provide a perforated thimble 40 which is provided at its inner end with an annular flange seat 42 secured by solder or other means to the thimble member 40. A circular screen 43 rests at the outer part 10 of the flange member 42 and the annular space between the thimble 40 and the screen 43 is filled with mineral wool 44, or other suitable filtering substance. The front member 29 is provided with circular bead grooves 15 45 and 46 in which the thimble 40 and the screen member 42 respectively seat. A resilient annular gasket 47 is positioned between the bag member 19 and the thimble member 42, so that when the thumb nut 31 20 is screwed up, the strainer member is held rigidly fixed in position within the air cleaner, forming a cylindrical chamber 48 into which the air must pass through the filter member 44 before reaching the cleaner outlet or carburetor inlet 25.

Where the filter member is used the air will first pass into the annular space around the filter member where much the larger part of the dust therein will be thrown to the 30 outer wall and gravitate through the opening 14 into the container 18. There may be in the air at times some very fine particles of dust which will tend to pass on with the current of air through the opening 21 into the 35 carburetor inlet 25. This dust-laden air will, if the filter member is employed, have to pass

through it and in doing so the dust borne by it will be caught and held, permitting the air to go on to the carburetor entirely relieved of such fine particles of dust.

40

I claim:

1. An air cleaner for carburetors comprising a cylindrical casing adapted to be mounted with its axis horizontal, means forming a dust-withdrawal opening at the bottom of 45 said casing, an airtight receptacle secured to said casing below said dust-withdrawal opening, an air inlet pipe extending horizontally and tangentially from the upper portion of said casing, a hollow filtering member in said 50 casing having its axis coinciding with the axis of the casing, and an air outlet pipe leading from the interior of said filtering member.

55

2. An air cleaner for carburetors comprising a cylindrical casing having a removable end wall and adapted to be mounted with its axis horizontal, means forming a dust-withdrawal opening at the bottom of said casing, an airtight receptacle secured to said casing 60 below said dust-withdrawal opening, an air inlet pipe extending horizontally and tangentially from the upper portion of said casing, a hollow filtering member removably held between the fixed wall and the removable 65 wall of said casing and having its axis coinciding with the axis of the casing, and an air outlet pipe leading from the interior of said filtering member.

60

In testimony whereof I hereunto affix my 70 signature.

ASHLEY C. BENNETT.
